UNITED STATES PATENT OFFICE

THOMAS BARISH, OF JAMESTOWN, NEW YORK

APPARATUS FOR TRUING GRINDING WHEELS

Application filed November 27, 1928. Serial No. 322,170.

This invention relates to grinding wheels, and particularly to grinding wheels utilized in the forming of raceways of ball bearings. It is desirable to form such raceways with compound curves in transverse cross section, that is, to have different curves forming the opposite sides of a raceway. For example, such curves may, in transverse section, be circular arcs having centers of curvature spaced apart in a direction transversely of the raceways, and with the radii of curvature of the two curves crossing or intersecting. Such raceways have heretofore been difficult to form, but may be formed by grinding the same to the desired shape by a grinding wheel or disk whose peripheral edge in transverse cross section corresponds to the two transverse sectional curves of the raceways.

An object of this invention is to provide an improved method and apparatus for forming the desired curves upon the periphery of the grinding wheel, and which will be relatively simple and practical.

A further object of the invention is to provide an improved apparatus for truing the edges of a grinding wheel or disk to the desired compound curves, with which the radii of curvature of two curves and the distance between the centers of curvatures of two curves may be varied, with which adjustment for wear on the grinding wheel may be made, and which will be relatively simple, compact and inexpensive.

Various other objects and advantages will be apparent from the following description of an embodiment of the invention, and the novel features will be particularly pointed out hereinafter in connection with the appended claim.

40 In the accompanying drawing:—

Fig. 1 is a plan of the truing machine, constructed in accordance with this invention;

Fig. 2 is an end elevation of the same, with 45 two parts partly broken away to better show other parts; and

Fig. 3 is a diagram illustrating the operation of the tool upon the wheel periphery.

In the illustrated embodiment of the invention, the grinding wheel 1, whose periph-

ery is to be trued or provided with a compound curve, is mounted in any suitable manner upon a shaft, which in turn is rotatably mounted in suitable bearings 3 and driven in a suitable manner, such as by a pulley 4 55 mounted on the shaft and operated by a belt from any suitable source of power. The bearings 3 may extend from a suitable base 5 having guideways 6 upon its upper face and extending parallel to the shaft 2.

A carriage 7 is mounted upon the base 5 and guided in movement by the guideways 6. The movement of the carriage along the ways 6 may be effected, and the carriage secured in adjusted positions, in any desired manner, such as by lugs 8 on the base 5 and screws 9 which pass through the lugs 8 and cooperate with the carriage 7 to move or secure it. The carriage 7 is provided with guides 10 which extend crosswise of the ways 6 and slidably mount a plate 11.

A suitable operating screw 12 passing through a lug or ear 13 on the carriage and engaging with the plate serves as a medium to shift the plate back and forth along the guides 10, and hold the plate in different adjusted positions. The plate 11 is provided with an arcuate strip 14, the arms of which extend from opposite sides of the plate and at their free ends are attached to the forward 80 end of the plate 11 by a cross strip 15.

A table 16 is pivotally attached, such as by a pivot screw 17, to the plate 11, so that the table may swing or oscillate sidewise, during which movement it will be guided by the arcuate strip 14. The table in turn is provided with guides 18 which extend radially toward and from the axis of the pivot screw 17, and a tool block 19 is mounted in the guides 18 for movement therewith. A screw 20 cooperates with the table and the block to shift the block along the guides 18 of the table and hold the block in adjusted positions.

A suitable forming tool 21 is removably secured upon the upper face of the block 19 in any suitable manner, such as by screws 22, and the working edge or nose of the tool extends into proximity to the periphery of the grinding wheel 1.

Assuming that the grinding wheel is being rotated through its shaft 2, the forming tool 21 is attached to the block 19, and the latter is adjusted until the working edge of the tool is at a distance from the extended axis of the bearing screw 17 corresponding to the corresponding radius of each curve. The screws 9 are then adjusted to place the pivot screw 17 at one of the desired centers of curvature, such as at one side of the other of the central plate of the grinding wheel and at a distance therefrom corresponding to the desired lateral displacement of the center of curvature of the desired curve from that plane.

The table is then oscillated about the screw 17, and the screw 12 operated to shift the plate 11 until the tool 21 engages with the peripheral edge of the grinding wheel. Thereupon the oscillations of the table will be effected between the position shown in Fig. 1 and one side of that position, back and forth until that side of the peripheral edge of the grinding wheel has the desired curvature.

Thereupon the screws 9 are operated to shift the carriage in a direction parallel to the shaft 2, a distance corresponding to the desired distance between the centers of curvatures of the two curves on opposite sides of the periphery of the wheel, and thereupon the table is again oscillated to true up or form the other side of the peripheral edge of the grinding wheel in a similar manner.

The operation is illustrated diagrammatically in Fig. 3, in which the paths of travel of the working edge or nose of the tool 21 is illustrated by the curves A and B shown extended in dash lines in that figure. The center of curvature of the curve A is represented at C, and the center of curvature of the other curve B is represented at C'. Similar curves A' and B' are separately illustrated with larger radii in the same figure, in order to illustrate more clearly, the relation between the curves A and B.

It will be noted that the two centers of curvature C and C' are spaced apart in a direction parallel to the axis of rotation of the wheel 1, and if the two sides of the peripheral edge of the wheel are to be symmetrical to one another, the centers of curvature C and C' will also be on opposite sides of and an equal distance from the central plane of the grinding wheel.

The centers of curvature C and C' will successively lie in the extended axis of the bearing or pivot screw 17, and thus the center of oscillation of the tool 21 will be shifted from one center of curvature to the other by the shifting of the pivot screw 17 in a direction parallel to the shaft 2.

It will be observed that the truing or forming of the compound curve upon the periph-

ery of the grinding wheel may be thus obtained in a simple and practical manner, and variations in the compound curves thus formed on the grinding wheel may be obtained by simple adjustments.

As the diameter of the wheel 1 decreases through use, the screw 12 may be operated to shift the plate 11 toward the wheel, and carry the tool into re-engagement with the grinding wheel, and thus take care of wear on the grinding wheel.

It will be understood that the apparatus illustrated is capable of various modifications within the principle of the invention, and that various changes in the details of construction and arrangement of parts may be made by those skilled in the art within the principle and scope of the invention as expressed in the appended claim.

I claim:

In a grinding wheel trimming device, the combination of a base, a grinding wheel rotatably mounted on said base, a carriage slidably mounted on said base adjacent said grinding wheel, means for laterally moving said carriage relative to said base, a plate slidably mounted on said carriage for movement toward and from said grinding wheel, an arcuate guide strip mounted on one end of said plate, a table pivotally mounted on the other end of said plate, said table having its free end guided by said arcuated strip, and a trimming tool mounted on said table for trimming the peripheral edge of the grinding wheel by movement across and in contact with the edge of the wheel.

THOMAS BARISH.
